UNITED STATES PATENT OFFICE.

LOUIS S. FLATAU, OF ST. LOUIS, MISSOURI.

TURBINE.

1,097,412.

Specification of Letters Patent. Patented May 19, 1914.

Application filed August 28, 1912. Serial No. 717,594.

To all whom it may concern:

Be it known that I, LOUIS S. FLATAU, a citizen of the United States, residing at St. Louis city, State of Missouri, have invented 5 certain new and useful Improvements in Turbine-Engines, of which the following is a specification.

My invention relates to an improvement in turbine engines and more particularly to 10 that type in which a constant flow of fluid under pressure from the nozzles against the vanes on a vane member journaled in juxtaposition to the nozzles causes the vane member to be rotated by the impact of the fluid 15 against the vanes.

The object of this invention is in the provision of a stationary vane member and two rotatable vane members, one mounted to revolve within the stationary member and the 20 other without, and a fluid chamber mounted to be stationary within the inner rotary vane member and having nozzles to direct the fluid against the inner vane member for turning it, and thence the fluid passes 25 through the stationary member and again exerts force upon the outer vane member, thus virtually providing a high and low pressure turbine.

A further object is in providing two sets 30 of nozzles disposed at different angles to drive the rotatable vane members in either forward or reverse direction and in the provision of means for controlling the passage of the fluid to one or the other of the sets of 35 nozzles or shutting off the flow to either.

A still further object is in the provision of a governor operating in conjunction with the rotatable vane members to control the supply of fluid to the fluid chamber and consequently maintain the speed of the engine 40 at a uniform rate.

With these objects in view, the invention consists of certain novel features of construction and combinations of parts which will be 45 hereinafter more fully described and pointed out in the claims.

In the accompanying drawings—Figure 1 is a vertical sectional view taken longitudinally of the axis of rotation of the several parts; 50 Fig. 2 is an enlarged view of the upper portion of the mechanism as shown in Fig. 1, more clearly to illustrate the detail parts; Fig. 3 is a view in top plan; Fig. 4 is a view in end elevation with the upper portion 55 section transversely of the axis of rotation; Fig. 5 is a sectional view on the line 5—5 of

Fig. 1, and Fig. 6 is a fragmentary sectional view to better illustrate the relative positions of the several sets of vanes and shows the travel of the driving fluid with 60 respect thereto in dotted lines.

On the base A a casing which is formed of the two halves B and C, is constructed and the halves have bearings 1 and 2 respectively formed thereon.

A stationary vane member D has its shank 3 received in the bearing 1 and is held against rotation therein by the key 4 or in any other suitable manner. The stationary vane member D is formed of the two shells 4 and 5 which are secured together and held spaced apart by the vanes 6 placed at regular intervals between the shells around their outer edges. Within the shank 3 of the vane member D a stem 7 connected with the flanged plate 8 is held against rotation by a key 9. A fluid chamber which comprises the wall 10 and side 11 is secured to the free face of the flange plate 8 by screws 12, 12, thus forming a fluid chamber 13. A rotary vane member E is received between the fluid chamber 13 and the stationary vane member D and has its shell 14 mounted to revolve on the stem 7 of the flange plate 8, and the opposite shell 15 mounted to revolve on a 85 stud bearing 16 formed on the face 11 of the fluid chamber. The shells 14 and 15 are held spaced apart by the vanes 16 which are in cross section similar to the vanes 6 of the stationary member D. A second rotatable vane member F is placed between the stationary member D and the casing B, C, and has its shells 17 and 18 journaled upon bearings 19 formed on the stationary member D and held spaced apart by the 95 vanes 20 similar to the vanes 6 and 16. The shells 15 and 18 are held against rotation with respect to each other by a key 21 which connects the vane members E and F to revolve together. On a hub 22 of the shell 18 a gear 23 is formed, and journaled on the stud shaft 24 carried by the plate 25 secured to the half C of the casing, are spur gears 26 which mesh with the gear 23 to be revolved as the members E and F are turned.

A drive shaft G is journaled in the bearing 2 on the half C of the casing and has connected thereto by a key 27 a flanged plate 28. The plate 28 is mounted in the casing with its flange inclosing the spur gears 26 and secured to the flange is an internal driving gear 29 which meshes with

the spur gears 26 and imparts power to the drive shaft G. The flange 11 has a plurality of radial counterbores 30 in its outer circumference. These counterbores 30 are 5 preferably arranged in pairs as better shown in Figs. 4 and 6 and between each pair the flange is cut away as at 31 with the side walls of the cut away portion preferably at an angle of 45 degrees to the counterbores 30. Plugs 32 are screwed or otherwise secured in the outer end of the counterbores 30 and ducts 33 disposed preferably at an 10 angle of approximately 45 degrees to the counterbores, are connected therewith and extend to the notched portion 31 of the rim. In each of the ducts 33 nozzles are secured, some of which, 34, are positioned to have their openings projecting in one direction, and the remainder of the nozzles, 35, are 15 positioned to have their openings projecting in the opposite direction and approximately at right angles to the nozzles 34.

The rim 10 has cross bores 36 which connect with the counterbores 30 and have their 20 outer ends in communication with the fluid chamber 13. As a means of controlling the passage of fluid to one or the other of the sets of nozzles 34 and 35, valves 37 are provided. These valves 37, as better shown in 25 Fig. 6, are formed of a single piece of sheet metal which is pivoted to the rim 10 by a pivot screw 38, and have one end projecting in position to cover both of the cross bores 36 to each set of counterbores 30, one of 30 which communicates with the duct to the nozzle 34 and the other to the nozzle 35. It will be understood that there is a valve 37 for each set of counterbores 30 and that the valve is intended to establish communication 35 through the opening 39 formed in its free end between one or the other of the counterbores 30 of the set, or to close both, as shown in Fig. 6.

As a means of supplying fluid to the fluid 40 chamber 13 a pipe 40 is controlled by a valve 41, which may be of the ordinary globe or any other approved type, and extends through the bearing 1 on the half B of the casing and within the stem 7 carrying the 45 flanged plate 8. A sleeve 42 is mounted to turn on the pipe 40 within the stem 7 and has secured to its outer end a throttle lever 43. As a means of controlling the valves 37, a grooved collar 44 is secured to the inner end of the sleeve 42 by a key 45. The 50 free inner ends 46 of the valves 37 are received in the grooves of the collar 44 and the pins 47 pass through the collar and through elongated slots 48 in the ends 46 of the 55 valves, whereby as the throttle lever 43 is turned the collar 44 is thus moved. The outer or opposite ends of the valves 37 may be shifted around their pivots at 38 to control 60 the passage of fluid through the nozzles 34 and 35.

As a means of maintaining a uniform speed in the engine under operation a governor valve 49, which is to all intents and purposes an ordinary cone valve, is positioned to be operated with relation to a seat 50 formed on that end of the pipe 40 which projects into the fluid chamber 13. The valve 49 has a stem 51 connected thereto which is held to revolve by a stud shaft 56 journaled in a bearing formed in the stud bearing 16^a and projects back through an axial bore 52 in the drive shaft. The stem 51 has a screw threaded bore at 54 in its outer end, and an adjusting screw is adapted to be fed into, or withdrawn from, the bore by turning with a screw driver or other instrument 55 due to its screw threaded engagement with the collar 56 secured to the end of the drive shaft G. The stud shaft 56 is connected to revolve with the drive shaft G by a pin 57 which is received through the drive shaft and an elongated slot 58 in the stem, thus providing for endwise movement of the stem and consequently of the valve toward and away from its seat. Wings 59, 59, 65 are formed on the stem 51 within the fluid chamber 13 and pivoted to the wings 59 are the governor weights 60 which carry the lugs 61 at their pivot points in position to be received in recesses 62 formed in the stem 51. In this way the centrifugal force exerted on the governor weights closes the valve and controls the supply of fluid. On the inner circumference of a ring J held 70 between the casing halves B and C vanes 64 are formed which project inwardly from the ring and are stopped short of the vanes 20 on the vane member F so that sufficient clearance will be allowed for the member F to be revolved adjacent the vanes 64.

The operation of the device is as follows: The valve 41 in the pipe 40 is opened; and the fluid, which may be steam, gas, or any other suitable medium, flows through the pipe 40 and into the fluid chamber 13. Assuming that the engine is to be driven in the direction indicated by the arrow in Fig. 4, the throttle lever 43 is turned to the left which throws the valves 37 in such a position that the openings therein communicate 75 with the cross bores 36 which lead to the counterbores 30 and ducts 33 in which nozzles 35 are connected. This permits the fluid to pass through the cross bore, counterbore and duct and out through the nozzle 35, after passing out through the nozzle 35 it hits against the faces *a* of the vanes 16 on the rotary vane member E from which it is guided back by the curve of the faces *a* against the faces *b* of the vanes 6 on the 80 stationary vane member D, and as the vanes 6 are stationary, the fluid is given a new force in the same direction in which it was expelled from the nozzle 35 by the curve of the faces *b*. The fluid passes outwardly 85

and strikes the faces *c* of the vanes 20 of the outer rotary vane member F, thus causing this member to revolve in the same direction as the member E. The curved faces *c* of the vanes 20 throw the fluid back and against the faces *d* of the vanes 64 formed on the ring J. It will thus be seen that the fluid has virtually four driving impacts. First, against the faces *a* of the vanes 16, back 10 against the faces *b* of the vanes 6, forward against the faces *c* of vanes 20, and then back again against the faces *d* of vanes 64, after which it passes out from the casing B, C through the exhaust opening 65.

15 The vane members E and F which are revolved by the fluid, are connected together and the gear 23 which is formed on the hub of the member F meshes with the spur gear 26 mounted on a part of the casing and 20 through their engagement with the internal drive gear 29 cause the drive shaft G to be driven for transmitting power.

It is intended that the pockets 65 and 66, which are formed on the casing halves B 25 and C respectively, shall at all times have oil or other suitable lubricant therein to the height of perhaps one-third to one-half the diameter of the pockets and in the pocket 65 a collar 67 is secured to revolve with the 30 vane member F to which collar carriers 68 are secured to cause the oil to be splashed or carried to suitable ducts connecting with the several bearings on that side of the casing. The internal driving gear 25 and its 35 connecting parts, and also the spur gear 26 in the pocket 66 will sufficiently agitate the oil in that pocket and will carry it to ducts connecting with the bearings contained within the half C of the casing and in the base 40 A an oil chamber 69 is formed which is connected by tubes 70, 70 with the oil pockets 65 and 66 and has a drain pipe 71 which is controlled by a stop cock 72 for removing the oil from the oil chamber 69 for cleaning 45 or any other purpose. Oil is introduced into the oil pockets 65 and 66 through the openings 73 in the upper walls thereof which are closed by caps 74.

As the temperature of the oil in the pockets 50 65 and 66 will be relatively higher than that in the chamber 69, a constant circulation will be forced from the pockets through the tubes 70 into the chamber and back into the pockets, thus permitting of the use of 55 a relatively large quantity of oil and maintaining it at a lower temperature than could otherwise be maintained. As a means of draining the oil from the bottom of the casing B, C, drain pipes 75 and 76 are connected on opposite sides near the bottom thereof.

It will, of course, be understood that if the engine is to be driven in a direction opposite to that described, the throttle lever 60 43 will be shifted to the right, thus opening

the passages to nozzles 34 and causing the fluid to make its impact against the opposite faces of the vanes 16, 6, 20 and 64, which would drive the shaft G in the opposite direction. As the speed of the engine increases above a certain point, the governor weights 60 in the fluid chamber 13 move more nearly to the perpendicular, due to the centrifugal force, causing the cams 61 to bear against the disk 62 and forcing valve 70 49 inwardly in closer relation to its seat 50 which decreases the supply of fluid passing from the pipe 40 and consequently reduces the speed of the engine.

It will thus be seen that I have provided 75 a turbine engine in which the fluid pressure has several driving impacts without materially increasing the quantity of fluid used and which may be driven forwardly or in reverse at equal speed and the same power, 80 and also that the engine, when traveling at full speed ahead, may be thrown to full speed reverse without straining various mechanism, as the fluid pressure upon the vane members acts as a cushion to absorb 85 the shocks which would otherwise result. Further, I have provided means whereby when once the engine is adjusted to travel at a predetermined speed, that speed is maintained regardless of the load under 90 which the engine is working by regulating the supply of fluid thereto.

Having thus described my invention, what I claim and desire to secure by Letters Patent is—

1. A turbine engine comprising a casing, a plurality of stationary vane members, a plurality of rotatable vane members mounted to revolve adjacent the stationary members, vanes carried by the inner circumferential wall of the casing, and nozzles positioned to discharge the motive fluid so that it directs an impact against the rotatable and stationary vane members alternately and lastly against the vanes of the casing. 100

2. A turbine engine comprising a casing, a plurality of stationary vane members, a plurality of rotatable vane members mounted alternately with respect to, and to revolve within, the stationary members, vanes carried by the inner circumferential wall of the casing, and nozzles positioned to discharge the motive fluid so that it directs an impact against the alternate rotatable and stationary members and lastly against the 115 vanes of the casing.

3. A turbine engine comprising a casing, a plurality of stationary vane members, a plurality of rotatable vane members, mounted alternately with respect to, and to revolve within, the stationary members, vanes carried by the inner circumferential wall of the casing, and a plurality of nozzles positioned to discharge the motive fluid against one of the rotatable vane members from 120 125 130

which it is deflected to one of the stationary members which in turn deflects the motive fluid to another of the rotatable members and the fluid continues its deflected course from 5 rotatable to stationary member out through the several vane members lastly exerting a driving impact against the vanes of the casing from whence it passes to the exhaust.

4. A turbine engine comprising a casing, 10 a plurality of stationary members, a plurality of rotatable members, vanes on each of said stationary and rotatable members, the rotatable members mounted alternately with respect to, and to revolve within, the said 15 stationary members, vanes carried by the inner circumferential wall of the casing, all of said parts so positioned that the vanes of the several members are in alinement, and nozzles mounted to discharge the motive 20 fluid against the vanes for causing the rotatable members to revolve.

5. A turbine engine comprising a casing, a plurality of stationary members, a plurality of rotatable members mounted alternately with respect to, and to revolve within, the stationary members, double faced vanes formed on the said stationary and rotatable members, vanes carried by the inner circumferential wall of the casing, and nozzles 25 positioned to discharge the motive fluid against the faces of the vanes on one of said rotatable members, from whence it is deflected to the back of the vanes on one of the stationary members, then to the face 30 of the vanes on the next rotatable member, and so on through the several vane members to the vanes of the casing from which it passes to the exhaust.

6. A turbine engine comprising a casing, 40 a plurality of stationary members, a plurality of rotatable members mounted alternately with respect to, and to revolve within, the stationary members, vanes on each of said stationary and rotatable members and 45 on the inner circumferential wall of the casing, a set of nozzles positioned to discharge the motive fluid against the face of the vanes on the rotatable members for imparting a forward rotation thereto, a second set of nozzles positioned to discharge the motive 50 fluid against the back of the vanes for imparting a reverse revoluble movement thereto, and means for controlling the supply of motive fluid to one or the other of said sets 55 of nozzles and for cutting off the supply entirely.

7. A turbine engine comprising a casing, a plurality of stationary members, a plurality of rotatable members mounted alternately with respect to, and to revolve within, the stationary members, double faced vanes formed on the said stationary and rotatable members, like vanes carried by the inner circumferential wall of the casing, a

set of nozzles positioned to discharge the 65 motive fluid against the faces of the vanes on one of said rotatable members, from whence it is deflected to the back of the vanes on one of the stationary members, then to the face of the vanes on the next rotatable member and so on through the several vane members to the vanes of the casing, from whence it passes to the exhaust, thus imparting a forward revoluble movement to the rotatable members, a second set 70 of nozzles positioned to discharge the motive fluid against the backs of the vanes on the rotatable members and the faces of the vanes on the stationary members for imparting a reverse revoluble movement to the rotatable members, and means for controlling the supply of motive fluid to one or the other of said sets of nozzles and cutting off entirely the supply of motive fluid. 80

8. A turbine engine comprising a casing, 85 a plurality of stationary vane members, a plurality of rotatable vane members mounted alternately with respect to, and to revolve within, the stationary members, vanes carried by the inner circumferential wall of the 90 casing, nozzles positioned to discharge the motive fluid against one of said rotatable members from which it is deflected to one of said stationary members, back again to a second rotatable member and continues in 95 its deflected course through the several vane members to the vanes of the casing, from whence it passes to the exhaust, thus revolving the rotatable members, a drive shaft, and means connecting the rotatable members with the drive shaft. 100

9. A turbine engine comprising a casing, a plurality of stationary vane members, a plurality of rotatable vane members mounted alternately with respect to, and to revolve within the stationary members, vanes carried by the inner circumferential wall of the casing, a stationary fluid chamber mounted within said stationary and rotatable members, nozzles connected with said 105 fluid chamber in position to discharge the motive fluid against the vanes of the several members whereby the rotatable members are caused to revolve, and means for supplying motive fluid to the fluid chamber. 110

10. A turbine engine comprising a casing, a plurality of stationary vane members, a plurality of rotatable vane members mounted alternately with respect to, and to revolve within, the stationary members, vanes 115 carried by the inner circumferential wall of the casing, a stationary fluid chamber mounted within said stationary and rotatable members, nozzles connected with said fluid chamber in position to discharge the 120 motive fluid against the vanes of the several members whereby the rotatable members are caused to revolve, means for supplying mo- 125

tive fluid to the fluid chamber, and a governor valve in the fluid chamber actuated by the movement of the rotatable members for governing the supply of motive fluid and thus maintaining a constant speed of the rotatable members.

11. A turbine engine comprising a casing, a rotatable member mounted in the casing, a stationary member received within the rotatable member, a second rotatable member mounted in the stationary member, vanes on each of said members having openings therebetween, vanes carried by the inner circumferential wall of the casing and nozzles positioned to discharge the motive fluid against the vanes of one of the rotatable members, after which it is deflected against the vanes of each of the other members, thus causing the rotatable members to be revolved.

12. A turbine engine comprising a casing, a rotatable member in the casing, a stationary member in said rotatable member, a second rotatable member in said stationary member, vanes carried by each of said members spaced apart to have openings therebetween and positioned to be in alinement with the vanes of each of the other members, vanes on the inner circumferential wall of the casing in alinement with the vanes of the several members, and nozzles positioned to discharge the motive fluid against the vanes of the second rotatable member which deflects it to the vanes of the stationary member which in turn deflects to the vanes of the first rotatable member and these vanes in turn deflect the motive fluid against the vanes of the casing from whence it passes to the exhaust.

13. A turbine engine comprising a casing, a rotatable member in the casing, a stationary member in said rotatable member, a second rotatable member in said stationary member, vanes carried by each of said members, vanes on the inner circumferential wall of the casing in alinement with the vanes of the several members, nozzles positioned to discharge the motive fluid against the vanes of each of said members and of the casing for causing the rotatable members to be revolved, a drive shaft, and means connecting the rotatable members with the drive shaft.

14. A turbine engine comprising a casing, a rotatable member mounted in the casing, a stationary member received in said rotatable member, a second rotatable member mounted in said stationary member, a fluid chamber secured within the second rotatable member, vanes carried by each of said members, a set of nozzles carried by the fluid chamber in position to discharge the motive fluid against the vanes for revolving the rotatable members in a forward

direction, a second set of nozzles positioned to discharge the motive fluid against the vanes to revolve the rotatable members in a reverse direction, and manually operated means for controlling the supply of fluid from the fluid chamber to each of said sets of nozzles and cutting off the flow thereto.

15. A turbine engine comprising a casing, a rotatable member mounted in the casing, a stationary member received within said rotatable member, a second rotatable member mounted in said stationary member, vanes carried by each of said members, nozzles positioned to discharge the motive fluid against the vanes of each of said members, means connecting the rotatable members to revolve together, a gear formed on one of said rotatable members, a drive shaft, a drive gear carried by said drive shaft, and spur gear carried by the casing to actuate the drive gear for transmitting power to the drive shaft.

16. A turbine engine comprising a casing, a rotatable member mounted in the casing, a stationary member received in said rotatable member, a second rotatable member mounted in said stationary member, a fluid chamber secured within the second rotatable member, vanes carried by each of said members, a set of nozzles carried by the fluid chamber in position to discharge the motive fluid against the vanes for revolving the rotatable members in a forward direction, a second set of nozzles positioned to discharge the motive fluid against the vanes to revolve the rotatable members in a reverse direction, manually operated means for controlling the supply of fluid from the fluid chamber to each of said sets of nozzles and cutting off the flow thereto, a fluid supply pipe connected with the fluid chamber, a governor valve in the fluid chamber for controlling the supply thereto through the fluid supply pipe, and a governor connected with said governor valve and actuated by the movement of the rotatable members.

17. A turbine engine comprising a casing, a rotatable member mounted in the casing, a stationary member received in said rotatable member, a second rotatable member mounted in said stationary member, a fluid chamber secured within the second rotatable member, vanes carried by each of said members, nozzles connected with the fluid chamber and positioned to discharge the motive fluid against the vanes of the several members for revolving the rotatable members, means connecting the rotatable members to revolve together, a gear formed on one of the rotatable members, a drive shaft, a drive gear carried by the drive shaft, spur gear carried by the casing meshing with said gear wheel and drive gear, a fluid supply pipe to the fluid chamber, manually oper-

ated valves for controlling the passage of fluid from the chamber to the nozzles, a governor valve received in the fluid chamber in position to control the supply of the fluid through the fluid supply pipe, said valve actuated by the movement of the rotatable members, and means for adjusting the governor valve to vary the passage of fluid through the fluid supply pipe and conse-

quently vary the speed at which the rotatable members revolve. 10

In testimony whereof I affix my signature, in the presence of two witnesses.
